(57) CLAIM

I claim the ornamental design for a handle for cultivator, as shown.

DESCRIPTION

FIG. 1 is a perspective view of my new design;

FIG. 2 is a top plan view thereof;

FIG. 3 is a front elevation view thereof;

FIG. 4 is a side elevation view thereof (the other side is the same);

FIG. 5 is rear elevation view thereof; and,

FIG. 6 is a bottom plan view thereof.

The broken line showing of the tool head is included for the purpose of illustrating environment and forms no part of the claimed design.

1 Claim, 2 Drawing Sheets

FIG. 2

FIG. 5

FIG. 4

FIG. 6

FIG. 3
